UNITED STATES PATENT OFFICE.

DANIEL T. BROWN, OF PAWTUCKET, RHODE ISLAND.

CLEANER-TRUNK.

SPECIFICATION forming part of Letters Patent No. 688,588, dated December 10, 1901.

Application filed November 10, 1900. Serial No. 36,048. (No model.)

To all whom it may concern:

Be it known that I, DANIEL T. BROWN, a citizen of the United States, residing at Pawtucket, in the county of Providence and State 5 of Rhode Island, have invented a new and useful Improvement in Cleaner-Trunks, of which the following is a specification.

This invention has reference to an improvement in trunks or ducts used in connection 10 with cotton-openers to separate the dust and leaf from the cotton.

The invention consists in the peculiar and novel construction by which the dust and other impurities are separated from the cotton, delivered onto an endless platform, and discharged from time to time into a suitable receptacle, as will be more fully set forth hereinafter.

Figure 1 is a side view, partly in section, 20 of my improved cleaner-trunk, showing the two end portions of the same, the central portion being shown as cut out to reduce the size of the drawing. Fig. 2 is a transverse sectional view of the trunk. Fig. 3 is a sectional view 25 of part of the endless platform.

Similar marks of reference denote corresponding parts in all the figures.

In the drawings, A indicates the supply-duct connecting the opener-machine with the 30 trunk A', and A² the duct connecting the trunk usually with a lapper forming the cotton into a lap. The trunk A' consists of a box closed at the top, bottom, and sides, but open, preferably, at both ends. The trunk is 35 divided into the upper passage or duct a, through which the cotton is blown, and the lower passage or duct a' by the grate a². The duct a' is divided into pockets by the trans- 40 verse partitions a³ a⁸, to which are hinged the doors a⁴ a⁴. The endless platform b is made of a series of overlapping cleats b' b', secured to one or more endless belts b², and is actuated by the pulleys b³ b⁸, secured to shafts, 45 on one of which the loose and tight pulleys b⁵ b⁴ are secured. The endless platform b is supported on the bottom of the trunk A'. The doors a⁴ a⁴ hang suspended by their 50 hinges and bear on the endless platform b in a slightly oblique position. They are held against the platform b by means of the weighted arms a⁵, secured to the pintle of the hinges on the doors, and are also held in their

raised positions by the weighted arms a⁵, as is shown in broken lines in Fig. 1. The weighted arms a⁵ also serve to operate the 55 doors.

The grate a² does not extend the full length of the trunk, the portion at the receiving end from the duct A to the first cross-partition a³ being a closed bottom, as is also the portion 60 a⁶ between the last cross-partition a³ and the trunk A².

When in use, the doors a⁴ a⁴ are in the nearly vertical position shown in Fig. 1 and form a series of chambers of which the plat- 65 form b forms the bottom. These chambers are preferably made air-tight by covering the edges of the doors with list or similar mate- rial to secure an air-tight joint without caus- ing excessive friction. When it is desired 70 to remove the accumulated dust, leaf, and similar material collected in the chambers, a belt connected with the loose pulley b⁵ is shipped on the tight pulley b⁴ to set the plat- form b in motion, and the door a⁴ nearest to 75 the discharge end c of the trunk is raised to discharge the material collected in the first chamber into the funnel c' of the duct lead- ing to the dust-room.

The several doors a⁴ are successively swung 80 upward and are held in this position until all the material is removed, when the doors are again lowered and the belt is shipped to the loose pulley. As the weighted arms a⁵ are on the outside of the trunk, as is shown 85 in Fig. 2, they serve to operate as well as sus- tain the door in both positions.

By the construction shown in the drawings 90 large chambers are secured for the reception of the dust and leaf, and the accumulated material may be removed while the machine is in operation without the loss of fiber and without distributing any dust in the room. The traveling platform forming the bottom 95 of the receptacles is supported along every part by the bottom of the trunk and forms with the doors air-tight chambers for the re- ception of the dust and leaf.

While I have described the operation of 100 cleaning the accumulated dirt from the floors of the compartments and emptying the same into the dirt-chute c' by first raising the gravity door or gate a⁴ nearest to said dirt-chute and then raising the next adjacent door, and

so on through the series, it will be noted that the apparatus may be made to automatically clean itself. This may be brought about by causing the endless floor b to move in the direction of the dirt-chute after considerable dirt has accumulated on the floor in each compartment and leaving the gravity-doors a^4 in their normal positions, so that the dirt lying upon the floor will be dragged under each of the swinging doors in turn until it is discharged from the end into the chute. The accumulated dirt, as well as the transverse joints in the floor itself, will serve to slightly swing the doors, and thus permit the dirt to escape under them in the outward movement of the floor. The floor of course may be operated at will at any desired interval or it may be run continuously at a very slow speed, and in either case the cleaning may be done by raising the doors in succession or letting them hang in their normal positions and permitting the machine to cleanse itself.

Having thus described my invention, I claim as new and desire to secure by Letters Patent—

1. The combination of a passage through which fiber is conveyed, a set of dirt-receiving compartments leading off from said passage and each separated therefrom by a grating or screen, two opposite sides of each of said compartments being constituted by depending doors having their lower edges resting normally upon the floor of said compartments, the said floor being adapted to be moved in its own plane to convey the accumulated dirt from the compartments and discharge the same.

2. The combination of a passage through which fiber is conveyed, a set of dirt-receiving compartments leading off from said passage and each separated therefrom by a grating or screen, two opposite sides of each of said compartments being constituted by depending doors having their lower edges resting normally upon the floor of said compartments, the said floor comprising an endless belt against which the lower edges of said doors normally rest and with which they form a close joint, and means for actuating said endless belt to convey the accumulated dirt from the compartments and discharge the same.

3. The combination of a passage through which fiber is conveyed, a set of dirt-receiving compartments leading off from said passage and each separated therefrom by a grating or screen, two opposite sides of each of said compartments being constituted by depending swinging doors having their lower edges resting by its own weight normally upon the floor of said compartments, the said floor be-

ing adapted to be moved in its own plane to convey the accumulated dirt from the compartments and discharge the same.

4. The combination of a passage through which fiber is conveyed, a set of dirt-receiving compartments leading off from said passage and each separated therefrom by a grating or screen, two opposite sides of each of said compartments being constituted by depending swinging doors having their lower edges resting by its own weight normally upon the floor of said compartments and provided with counterbalancing-weights, the said floor being adapted to be moved in its own plane to convey the accumulated dirt from the compartments and discharge the same.

5. The combination of a passage through which fiber is conveyed, a subjacent chamber communicating with said passage and separated therefrom by a screen, a series of depending swinging doors mounted at intervals in said chamber and dividing it into a series of dust-receiving compartments, the said doors resting at an angle with their lower edges on the floor of said chamber, the said floor being capable of being moved in its own plane to convey the dirt accumulated thereon from said compartments.

6. The combination of a passage through which fiber is conveyed, a subjacent chamber communicating with said passage and separated therefrom by a screen, a series of depending swinging doors a^4 mounted at intervals in said chamber and dividing it into a series of dust-receiving compartments, the said doors resting at an angle with their lower edges on the floor of said chamber, the said floor comprising an endless belt against one stretch of which the edges of said depending doors rest, substantially as described.

7. The combination of a passage through which fiber is conveyed, a subjacent chamber communicating with said passage and separated therefrom by a screen, a series of depending swinging doors a^4 mounted at intervals in said chamber and dividing it into a series of dust-receiving compartments, the said doors resting at an angle with their lower edges on the floor of said chamber, the said floor comprising an endless belt or platform b provided with transverse strips or members b' against which the lower edges of the depending doors rest, substantially as described.

In testimony whereof I have signed my name to this specification in the presence of two subscribing witnesses.

DANIEL T. BROWN.
